CLAIM

I claim the ornamental design for a gourmet bowl maker, as shown.

DESCRIPTION

FIG. 1 is a perspective view of my gourmet bowl maker showing my new design;

FIG. 2 is a side view of my gourmet bowl maker.

FIG. 3 is a top plan view of my gourmet bowl maker.

FIG. 4 is a cross-sectional view taken along line 4—4 of FIG. 3; and,

FIG. 5 is a bottom plan of my gourmet bowl maker.

1 Claim, 2 Drawing Sheets

FIG. 1

FIG. 4
